UNITED STATES PATENT OFFICE.

ROBERT McC. JOHNSTONE, OF ROSELLE PARK, NEW JERSEY, ASSIGNOR TO CAMERON MACHINE COMPANY, OF BROOKLYN, NEW YORK, A CORPORATION OF NEW YORK.

METHOD OF AND MEANS FOR HANDLING WEBS OF FLEXIBLE MATERIAL.

Application filed December 3, 1923, Serial No. 678,335. Renewed June 15, 1926.

This invention relates generally to a method of and means for handling webs of flexible material and has more particularly reference to a method of and means for 5 handling materials such as tinfoil.

In the art of making tinfoil with one polished and one dull surface, it is customary to run a double thickness of material through the mill, the outer sides of the double thickness that come in contact with the rolls of the mill being highly polished and the inner sides, that are in contact with each other, being dull. The main object and feature of this invention is to devise an effective and simple method of and mechanism for separating and winding the double thickness and, also, if desired, to slit the material.

In the accompanying drawings the invention is disclosed in a concrete and preferred form in which—

Fig. 1 is a vertical sectional view through a slitting and winding machine embodying the invention and by means of which the 25 process may be carried on.

Fig. 2 is a fragmentary detail view of the means for driving the guiding rollers positively.

Fig. 3 is a diagrammatic view showing 30 the process that can be carried out in the machine.

The double thickness of material 4 consisting of webs 1 and 2 is run through the tinfoil rolling mill and is then wound on 35 reel 3 which latter is then placed in the separating and winding machine. As previously explained, the outer sides of the double thickness are highly polished and the inner adjacent sides are dull. It is desired 40 to separate the double thickness of material into two single layers and to wind such layers on separate winding shafts. The demands of the trade require that the highly polished side or surface of each web 45 be wound outermost so that after separating the webs they are wound with opposite sides outermost on separate winding shafts.

Double thickness 4 is led over guide 5 and 50 thence over nip roller 6 to the underside of guide roller 7 where the double thickness is separated, web 1 passing to winding shaft 8 and web 2 to guide roller 9 and thence to winding shaft 10. If desired, the double 55 thickness is slit by cutters 11, in this in-

stance acting against guide roller 7. Any sort of cutters, either shear or score, may be used and the cutting means may be independent of or combined with the guiding or winding means as is well understood in the art. 60 Guide rollers 7 and 9 are positively driven as by gears 12, 13 and 14 and rotate in opposite directions. Winding shafts 8 and 10 are frictionally driven, also in opposite directions, by contact with the guide rollers, 65 as shown, and are displaceable as the diameter of the wound material increases and counterweighted preferably in the manner shown in U. S. Letters Patent No. 1,256,499. It will also be noted that when 70 the webs are slit, all the sections of one layer or web are directed to one winding shaft and all the sections of the other layer or web are directed to the other winding shaft. 75

I claim:

1. Separating and winding mechanism for two superimposed webs of flexible material comprising: two oppositely rotating winding shafts, a guide roller for receiving the 80 double thickness of material and for guiding one of the thicknesses to one of said winding shafts, and a second guide roller for receiving the other thickness of material from the first guide roller and to guide 85 said other thickness to said other winding shaft.

2. Separating and winding mechanism for two superimposed webs of flexible material comprising: two oppositely rotating winding shafts, two oppositely rotating guide rollers one adjacent to each shaft and each of said guide rollers rotating in a direction opposite to that of the winding shaft to which it is adjacent, one of said guide rollers 95 receiving the double thickness of material and guiding one of said thicknesses to the winding shaft adjacent to it and guiding the other of said thicknesses to the other guide roller, and the other guide roller receiving said other thickness from the first guide roller and directing it to the winding shaft adjacent said other guide roller. 100

3. Separating and winding mechanism for two superimposed webs of flexible material 105 comprising: two positively driven and oppositely rotating guide rollers, two displaceable winding shafts one driven by frictional contact with one roller and the other driven by frictional contact with the other roller, 110

one of said guide rollers receiving the double thickness of material and directing one thickness to the winding shaft in contact with it and directing the other thickness of material to the other guide roller, and said other guide roller receiving said other thickness from the first guide roller and directing it to the winding shaft in contact with said second guide roller.

10 4. Separating and winding mechanism for two superimposed webs of flexible material comprising: two winding shafts, and guide rollers for separating the webs and for directing one web, with one of its sides 15 outermost, to one winding shaft and the other web, with the opposite side outermost, to the other winding shaft.

5. Separating and winding mechanism for two superimposed webs of flexible material comprising: two winding shafts, and 20 guide rollers for separating the webs and for so directing them to the winding shafts that

both webs are wound with the outer sides of the double thickness outermost, one web on one winding shaft and the other web 25 on the other winding shaft.

6. The herein described method of handling flexible materials which consists in separating a double thickness of material while it is advancing into two single layers, 30 and winding one layer separately from the other layer with opposite sides outermost.

7. The herein described method of handling flexible materials which consists in separating a double thickness of material 35 while it is advancing into two single layers, and winding one layer separately from the other layer with the outer sides of the double thickness outermost.

Signed at New York city in the borough 40 of Brooklyn, county of Kings and State of New York, this 28 day of November, 1923.

ROBERT McC. JOHNSTONE.
